UNITED STATES PATENT OFFICE.

EDWARD S. ROLAND, OF CLEVELAND, OHIO.

TROLLEY WHEEL AND HARP.

No. 845,900.

Specification of Letters Patent.

Patented March 5, 1907.

Application filed October 19, 1905. Serial No. 283,450.

To all whom it may concern:

Be it known that I, EDWARD S. ROLAND, a citizen of the United States, residing at Cleveland, in the county of Cuyahoga and State of Ohio, have invented certain new and useful Improvements in Trolley Wheels and Harps; and I do declare that the following is a full, clear, and exact description of the invention, which will enable others skilled in the art to which it appertains to make and use the same.

My invention relates to improvements in trolley wheels and harps, and the improvement consists in the construction and arrangements of parts substantially as herein-after shown, and more particularly pointed out in the claims.

The object of my improved device is embodied in the means for conveying the current centrally through the wheel and axis to the pole and in the separable construction of the wheel, as well as in other details of construction adapted to make a simple and durable device.

In the accompanying drawings, Figure 1 is a side elevation of my improved wheel and harp with a portion of the trolley-pole therefor. Fig. 2 is a central longitudinal section on line *x-x*, Fig. 1. Fig. 3 is a cross-section on line *y-y*, Fig. 1, of the harp, showing the recessed portion therein for the locking conductor-wire. Fig. 4 is a sectional view of the three separable elements comprising the trolley-wheel detached from each other. Fig. 5 is a side elevation of the central member of the trolley-wheel and a cross-section of the supporting-shaft and showing the contact-spring between said parts.

Wheel A comprises three separate members 2, 3, and 4, respectively, detachably secured together and jointly supported upon shaft B, fixed within the upper ends of harp C, which is pinned to trolley-pole D. Wheel members 2 and 3 are similarly-constructed concave-convex disks with central hubs and are reversely mounted upon opposite sides of member 4 and are preferably made of cast-iron and provided with steel bushings 5. Central wheel member 4 has a concaved peripheral surface and is of less diameter than members 2 and 3 and has integral projections 6 at each side, adapted to enter openings 7 in the side members. Projections 6 are struck up at their outer ends to rivet and lock said parts together. Central member 4 has a central open body adapted to provide oil-cham-

bers 8 between arms 9, which connect outer rim 10 with hub 11, and arms 9 are grooved transversely on their face at 12 to provide open communication between the chambers. 60 A screw-plug 25 closes a filling-opening in side member 2. Rim 10 has beveled side faces to correspond to the flaring portion of side members 2 and 3. The greatest wear upon the wheel naturally falls upon central member 4 because of its direct contact with the trolley-wire and also because it is preferably constructed of brass to provide a good conductor for the electric current. Whenever central member 4 is worn out, sides 2 70 and 3 are removed and a new like member replaced therefor.

Shaft B is preferably made of brass, because it also becomes a conductor for the current, and when cast a pair of steel bushing-rings 14 are cast thereon to encircle reduced portions 15 on said shaft and which when in place within wheel A are adapted to lie opposite and within bushings 5 of the wheel. A suitable irregular-shaped spring 16, of brass, is inserted between bushings 5 and is adapted to bear against the inner wall of hub 11 and also against shaft B at a point between the two bearing-rings 14. Spring 16 has free ends and is formed to contact with the shaft 85 and member 4 at different radial places, so that a good current-conductor is always to be had between rotating member 4 and fixed shaft B.

The means for holding shaft B within the 90 ends of arms 17 of harp C comprises a pair of locking-wires 18, one at each side of the harp, the upper ends of which are adapted to enter openings 19 in the side near the ends of shaft B. Wires 18 are preferably of brass to provide good conductors for the current, and the lower ends thereof are seated in a pocket or recess 20 at or near the bottom of each arm 17, and said wires also lie in a vertical grooved portion 22 of sides 17. To remove the wheel from the harp, it is only necessary to bend wires 18 outward and withdraw them from their seats and disengage them from openings 19 in shaft B, thereby permitting said shaft to be moved endwise from the harp and wheel, and thus unmount the wheel. 105

Central brass member 4 and brass shaft B, with brass contact-spring 16 between said parts, provides a direct path for the current from the trolley-wire to the pole without endangering the bearings for the wheel.

A further advantage of my improved con-

struction is in its separable construction, whereby when one part or another becomes worn a new part may be readily substituted and the remaining good parts again used.

5. The oil within chambers 8 seeps down between side members 2 and 3 and hub 11 and fills the circular chamber within which spring 16 is confined and with which the bearing-bushings are in open relation, thereby lubricating all the wearing-points between the wheel A, spring 16, and shaft B. When bushings 5 become worn, they can be driven from their seat and replaced.

Obviously the wheel may be solid; but a 15. sectional wheel is preferred, and particularly one having the novel construction herein shown and described.

What I claim is—

1. A trolley-wheel having a central current-conducting member, separate side members between which said central member is mounted, separate bushings for said side members terminating at said central member, a current-conducting shaft having separate bearing-rings within said bushings, and a harp adapted to support said shaft and wheel.

2. A trolley-wheel having separate sides and a bushing within each side, a shaft for said wheel having separate bearing-rings over which said bushings are sleeved, a current-conducting contact member for said wheel and shaft between said sides and a conductor within the same adapted to contact with said shaft and said contact member at different points about the shaft, and a support for said shaft and wheel.

3. The combination of a trolley-wheel comprising a central member and separable side members, with a shaft having bearing-bush-

ings for the said side members, a contact-spring for said central member and said shaft, and a harp adapted to support said shaft and wheel.

4. The combination of a trolley-wheel comprising a central member and separable side members, with a shaft and separate steel bushing members for said shaft and said side wheel members, a contact member for said central wheel member and said shaft, a harp adapted to support said shaft and wheel, and locking members between said shaft and harp.

5. The combination of a trolley-wheel comprising a central member having side locking 55 projections and side members having openings adapted to receive said locking projections, in combination with a shaft and harp adapted to support said wheel, and a spring within said central member constructed to 60 contact therewith and with said shaft at different radial positions at intervals about the shaft.

6. A trolley-wheel comprising a central ring member and side disk members having 65 steel bushings, in combination with a shaft having separated steel bearing-rings with a contact portion between them, a contact-spring engaged with said central member and said shaft-contact portion, and a harp adapted to support said shaft and having removable locking-wires at each side adapted to engage with the ends of said shaft.

In testimony whereof I sign this specification in the presence of two witnesses.

EDWARD S. ROLAND.
